UNITED STATES PATENT OFFICE.

FERDINAND ITTNER, OF BROOKLYN, NEW YORK, ASSIGNOR TO THE BRADFORD CO., OF MIDDLETOWN, CONNECTICUT, A CORPORATION OF CONNECTICUT.

GASOLENE-VAPORIZER.

1,106,452.

Specification of Letters Patent. Patented Aug. 11, 1914.

Application filed February 27, 1911. Serial No. 611,156.

To all whom it may concern:

Be it known that I, FERDINAND ITTNER, a subject of the Emperor of Austria-Hungary, and a resident of Brooklyn, in the 5 county of Kings and State of New York, have invented certain new and useful Improvements in Gasolene-Vaporizers, of which the following is a specification.

My invention relates to means for sup- 10 plying a combustible mixture of air and vapor to internal combustion engines and its object is to secure a complete vaporization of the gasolene or other hydrocarbon entering into the mixture and to furnish a per- 15 feetly dry gas to the engine at all times.

To these ends my invention consists in the improved devices and combinations of devices hereinafter described and then more particularly specified in the claims.

20 In the accompanying drawings, Figure 1 is a general central section of apparatus embodying my invention. Fig. 2 shows in enlarged side elevation the electric heater plug detached from the supply pipe. Fig. 3 is a 25 general side elevation of the fan or rotating element of the vaporizer removed from its position in the apparatus. Fig. 4 is a plan of the vaporizer with its top plate or inclosing dome removed. Fig. 5 is an en- 30 larged central section of the vaporizer taken on a line at right-angles to the view of Fig. 1.

1 is a pipe through which the mixture or gas is supplied to the manifold of a gas engine and 2 indicates in side elevation the 35 outlet end of a carburetor of any desired type employed for the purpose of producing a mixture of air and gasolene or other hydrocarbon. 3 indicates the throttle controlling lever thereof whereby the supply of the mixture of air and gasolene from the carburetor to the engine may be controlled.

4 indicates a vaporizer constructed as will be presently described and having an inlet 5 suitably constructed for connection to the 45 pipe leading to the carburetor and an outlet 6 for connection to the pipe 1 leading to the engine or manifold.

The vaporizer is preferably constructed as a casting having an inner shell 4' and outer 50 shell 4 separated by an annular space through which a heating medium such as the exhaust or other heating medium as for instance the water from the cooling jacket of the engine, may be circulated for the pur- 55 pose of heating the wall of the inner shell 4',

which wall, as will be presently described, receives on its inner surfaces the particles or drops of any liquid thrown on to the same by the action of a dispersing cone or by the centrifugal action of the fan mounted within said inner shell. The heating medium is introduced into the space or heating jacket through the inlet 7 and carried away therefrom by the outlet 8 or vice versa.

60 Mounted within the inner shell and upon an axis preferably coinciding practically with the axis of the shell is a rotatable device 9 in the form of a fan adapted preferably to be self-rotated by the action of the stream of air passing from the carburetor through the vaporizer to the engine. The fan 9 is preferably constructed with its hub 9' and vanes cast in one piece and the vanes of the fan or fan wheel are sufficient in number or of sufficient width to practically intercept the whole stream of the mixture and catch upon their surfaces any free particles or drops of gasolene or hydrocarbon therein. The vanes are inclined to the plane of the fan as shown, in order to cause it to be propelled at a high speed by the action of the stream of the mixture and to throw off by centrifugal force the particles or drops of liquid lodged thereon and cause them to come into contact with the inner wall of the 85 internal shell 4' or with parts in direct conducting connection therewith. The fan rotates freely on pivot bearings 10, 10', or is otherwise suitably mounted to rotate in a supporting frame 11. The said frame comprises preferably a ring 12 having diametrical cross-bars between which the blades of the fan rotate and said frame is itself mounted upon a ledge 13 within the shell 4' and is fastened down in place by an inwardly extending flange 14 on the bottom of the cover or dome 15, as clearly shown in Fig. 5. The under side of the frame has a conical projection 16 extending axially to meet the stream of the mixture introduced through the inlet 5 so as to throw off against the walls of the shell 4' particles or drops of liquid hydrocarbon encountered in the mixture or by reason of its heated condition to cause the same to vaporize. Any particles or drops which do not encounter the cone and pass on to the fan are received by the blades of the latter and thrown off by centrifugal action against the heated inner wall 100 of the shell and there vaporized.

110

By mounting the fan in bearings both of which are formed or supported on the frame 11 and properly supporting the same in the top portion or end of the vaporizing chamber with the conical projection extending axially toward the inlet 5, with which the pipe leading from the carburetor is connected, it will be seen that no obstacles are interposed to the free flow of the mixture and that the stream is received in a uniform manner by the cone and fan, thus insuring a complete vaporization of the particles in the mixture and avoiding any tendency of the stream to become localized on any part of the frame or supports for the fan.

17 is an additional throttle interposed in the passage between the vaporizer and the engine. Said throttle is preferably mounted in the cover or dome 15 in any desired manner upon a rock shaft 18 provided with an operating arm 19 and suitable mechanical connections as indicated are preferably made between the latter throttle and the throttle arm 3 of the carburetor, so that the two will open and close together. By this means not only is the supply of mixture from the carburetor to the vaporizer cut off at will but likewise and at the same time the supply of the vapor to the engine is cut off, so that any residual gas or vapor in the vaporizer cannot pass to the engine when the throttle controlling the supply from the carburetor to the vaporizer is operated.

The pipe or passage 1 between the vaporizer and the engine is constructed for the reception of an electric heater plug 20 which may be screwed into the opening properly formed in the side of the pipe 1 and is provided at its inner end with a heating electric coil 21, as shown more clearly in Fig. 2, which heating coil takes the place in the plug of the ordinary spark points of a spark plug and when heated by an electric current under control of the driver by means of a suitable switch, will heat the combustible gas or vapor circulating through the pipe 1 on its way to the manifold and engine. The heater plug 20 may be constructed on the plan of the usual spark plug modified preferably however by extending the central conducting rod 22 of the usual spark plug sufficiently to allow the desired length of heating coil 21 to be wound thereon. The mica or other insulation 23 is extended over the projecting end of the pin 22 to provide insulation of the turns of the heating coil 21 from one another and from the pin, and one end of said coil is attached directly to the end of the rod 22 and the other end of said coil to the pin 24 forming the other terminal or electrode of the plug.

The carburetor operates in the usual manner to produce as complete and perfect a mixture of the gasoline and air as is practicable. On starting the engine and when

the vaporizer has not become thoroughly heated, the driver turns current into the electric heating plug, thus heating the mixture on its way to the manifold and aiding in the ready starting of the engine. As soon as the same is fully in operation, the electric heater may be electrically disconnected. In the normal operation or after the engine is fully running, any free particles or drops of gasoline or other hydrocarbon passing from the carburetor and existing in the central portion of the stream of the mixture will be caught on the cone 16 and will eventually be vaporized as soon as the same becomes heated up through its metallic connection with the heated walls of the inner shell 4. The outer portions of the stream or any portions whose moist particles may not be caught by the cone, will encounter the vanes of the fan 9, which as soon as suction is fully established, will revolve by the action of the stream of the mixture and at high speed when the same is mounted on bearings suitably constructed to have little friction. These particles received on the vanes of the fan however, will be immediately dislodged therefrom by centrifugal action and will be thrown against the hot surfaces on the inner wall of the vaporizer, which is now jacketed by a layer of hot products of combustion received from the engine or by the heated water taken from the cooling jacket thereof, as may be desired. The consequence is that all of the gasoline or other hydrocarbon introduced in the carburetor and entering into the mixture, will, if not vaporized in the carburetor itself, be fully and completely vaporized, thus affording a perfectly dry gas for supply to the engine through the pipe 1 leading to the manifold. Owing to this complete vaporization, the engine will operate at a much higher efficiency than is possible when the mixture is supplied direct from the carburetor and with consequently a greater or less amount of free moisture of gasoline in the gas when it reaches the manifold.

In the ordinary operation of an automobile engine it is frequently necessary to slow down the engine quickly and for a short period of time, as for instance in driving the car through heavy traffic. The operation of the carburetor throttle alone is not effective for this purpose, for altho' the throttle 115 may be quickly closed, the engine will not slow down immediately. To aid in slowing down I provide the additional throttle 17 in the passage leading from the vaporizer to the engine and connect said throttles so 120 that they are operated practically as one. This additional throttle operated in connection with the usual carburetor throttle permits the engine to be slowed down almost instantly, as by its means the supply of com- 125 130

15 combustible gas from the vaporizer to the engine is effectually cut off. During momentary slowing-downs of the engine by the operation of the combined throttle, the fan, being 5 made rather heavy and being mounted to revolve freely, will continue to revolve at high speed and when the power is turned on suddenly, will be in condition to receive any free particles of moisture and cause vaporization of the same in a manner already described. It will therefore be seen that at all 10 times the combustible portion of the gas or mixture will be supplied to the engine in a thoroughly vaporized condition and therefore 15 in best condition for efficient operation.

By constructing the pipe 1 leading to the manifold in proper manner to receive the electric heater and by using said heater in the manner described, I attain by the use of 20 one heater practically the same results that could be obtained by the use of a heater plug for each cylinder of the engine.

As will be seen, my invention requires no special construction of carbureter shell but 25 may be used indifferently with carbureters of any construction, it being necessary merely to cut the connection from said carbureter to the engine and interpose the vaporizer between the outlet pipe from the 30 carbureter and the continuation of the pipe leading to the engine.

What I claim as my invention is:—

1. The combination of a vaporizing chamber having a heating jacket comprising an 35 inner shell and an outer shell separated by a space for circulation of a heating medium, a self-rotating fan mounted within said chamber and adapted to deliver any moisture deposited upon its blades directly 40 against the heated wall of said chamber formed by the inner shell by a centrifugal action, a carbureter, means for connecting the inlet of said chamber with the carbureter for delivering the mixture produced in the 45 carbureter to the vaporizing chamber and means for connecting the outlet of the vaporizing chamber with the engine manifold.

2. A vaporizer for hydro-carbon mixture, comprising a shell having a heating jacket 50 and an inlet adapted for connection to a pipe leading from the carbureter, a freely rotating fan mounted on an axis in line with said inlet and adapted to be rotated by the stream of mixture received through the inlet and a dispersing cone provided with a

bearing for the fan and projecting axially toward the inlet of the shell.

3. In a vaporizer for hydro-carbon mixture, a vaporizer shell having a heating jacket and a frame mounted in one end 60 thereof and carrying the fan, both bearings of which are on the frame, said frame being provided with a dispersing cone projecting toward an inlet adapted for connection to the pipe through which the mixture is received and delivered into a space containing the fan and cone.

4. A vaporizer consisting of a self-rotating fan, a double walled shell within which the fan is centrally mounted as to both bearings, a frame supported in one end of the shell and carrying said fan in position to deliver, by centrifugal action against the inner wall of the shell, any moisture deposited upon its blades in the stream of mixture received through the opposite end of the shell, inlet and outlet openings in said shell arranged in line with the axis of the fan and a moisture receiving cone projecting in line with the axis of the fan from a supporting frame thereof toward the inlet.

5. A vaporizer having a shell provided with inner and outer walls to afford space for a heating medium and with an inlet at one end adapted for connection with the 85 pipe through which the mixture is delivered to the same, a removable fan supporting frame mounted in the opposite end of the shell and having a cone projecting toward the center of the said inlet, and a self-propelled fan mounted in said frame co-axially with the axis of the inlet.

6. A vaporizer for a hydrocarbon mixture, comprising a shell provided with inner and outer walls to afford a space for circulating a heating medium, a frame mounted on the inner wall of the shell, a fan mounted in said frame with its axis in line with the inlet opening to the space closed by the inner wall and a dome provided with an outlet 90 passage and engaging the frame to hold it in place, as and for the purpose described.

Signed at New York in the county of New York and State of New York this 18th day of February A. D. 1911.
